ADJUSTMENT CONTROL UNIT FOR A CHAIR

Alan W. Speicher, Boonville, and Robert H. Godwin, Evansville, Ind., assignors to Bliss & Laughlin Industries, Incorporated, Oak Brook, Ill., a corporation of Delaware

Filed Aug. 3, 1967, Ser. No. 8,110

Term of patent 14 years

U.S. Cl. D15—1
Int. Cl. D8—03

Fig. 1.

Fig. 2.

FIG. 1 is a perspective view of an adjustment control unit for a chair as viewed from a point above and to the right rear thereof, showing our new design.

FIG. 2 is a perspective view thereof as seen from a point below and to the left front of the chair controller.

The dominant features of our design reside in those portions shown in full lines on the drawing.

We claim:

The ornamental design for an adjustment control unit for a chair, as shown and described.
